W. W. WOODRUFF

PROTECTIVE DEVICE

Filed Nov. 3, 1922

FIG. 1.

FIG. 2.

FIG. 3.

Inventor

W. WARREN WOODRUFF

By his Attorney

Howard W. Smith

UNITED STATES PATENT OFFICE.

W. WARREN WOODRUFF, OF SWARTHMORE, PENNSYLVANIA.

PROTECTIVE DEVICE.

Application filed November 3, 1922. Serial No. 598,733.

My invention has to do with a small unit or accessory which is particularly adapted to protect large or expensive pieces of apparatus from being destroyed by reason of the existence of abnormal operating conditions. The unit may be considered as a cut out, that is, an article which operates to prevent further operation of all or a part of a selected apparatus or a system. The unit may be employed for many different purposes and in conjunction with many different types of apparatus, but I have found that it has a particularly successful use when employed with transformers mounted in electrical power transmission lines. The description of the unit and its use will therefore be made in connection with this particular type of apparatus, although I desire that it be understood that the unit may be employed with other apparatus and particularly with other electrical apparatus.

It is well known in the transmission of electrical power from the generating station to the consumer, that the greatest efficiency is obtained by the use of transformers installed at selected points. Usually these transformers are located in isolated places where persons seldom pass so that the danger of accident from the high voltages is reduced to a minimum. Or when the transformers are employed at factories, they are so located and protected so that persons without authority are unable to come within the zone of danger, consequently the working conditions of the transformers are observed but seldom.

Since it has been found in practice that the best method of rating a transformer as to its continuous k. v. a. capacity is by determining the maximum temperature at which it is safe to operate the internal insulation at constant load, it has heretofore been necessary to periodically observe the temperatures of the parts of the transformers in order to operate them at their best efficiency. When the transformers are erected in the power house the temperatures may be readily observed by an operator but he must necessarily come within close prox-

imity with the dangerous high tension wires. When the transformers are located away from the power house, the user has elected to eliminate the cost of men, for inspection, by increasing his installation costs by purchasing transformers of larger capacity which operate at a much lower efficiency. It therefore becomes desirable to eliminate this extra initial cost and to operate the transformers at their best efficiency while at the same time protecting them from destruction when operated at dangerous temperatures.

The best present practice in the construction of transformers is to immerse the core and the windings in an oil bath and to provide as large a cooling surface as possible for the oil. However, the rating of a transformer is still based upon the maximum temperature for the continuous k. v. a. capacity. By reason of the nature of the load curve on most transmission systems, the transformers are loaded to rated capacity for only a very small portion of the time, and when it is considered that each transformer has a large thermal capacity, which requires about ten hours to reach maximum temperature under rated load, it is seen that the temperature remains much below its permissible value thereby decreasing the efficiency of the transformer to a very low point.

It has been the practice in the recent past to operate transformers at higher ratings and temperatures in order to take advantage of the installed k. v. a. capacity of a transmission system. The present rating of a transformer is of little value, as the determining factor is the temperature attained during the load cycle. Already several different types of temperature indicating devices have been developed, but each one requires that an attendant be employed to record the temperatures, and none of these devices operate to protect the transformer from being burned out which necessitates the expense of dismantling and the rewinding of the coils.

My invention therefore consists, in general, of an accessory which is readily in-

corporated in an apparatus so that it will operate under predetermined conditions to protect the apparatus from injury. More in particular, my invention consists of a novel association and operation of elements forming an accessory for electrical apparatus so that when assembled therewith it will be influenced by the operating conditions of such apparatus to cut off the power and thereby prevent destruction of the apparatus.

As has been heretofore stated, my device is especially adapted for use in transformers and I have therefore constructed it in a novel fashion which permits it to be affected by the temperature of the cooling medium such as oil flowing in a transformer and is so arranged as to have this cooling medium operate as an extinguisher for the arcs created when the power circuit to the electrical portions of the transformer is opened.

A proper conception of my invention may be readily obtained by considering its operation in connection with one of its successive uses, that is, on a transformer. Usually a unit is mounted in series with each lead-in conductor of the transformer and is immersed in the circulating oil. The unit carries separable contacts and is provided with a temperature responsive alloy to hold the contacts in current conducting relation. The oil is permitted to flow in and around the contacts and the alloy. When the temperature of the oil has reached a value, by reason of the operation of the transformer, which makes it dangerous to further operate the transformer, the alloy is fused and the contacts are allowed to automatically separate thus interrupting the flow of current. This oil, which is the circulating medium performs another function besides melting the alloy. It acts to extinguish the arc formed between the contacts as they separate thereby preventing injury to the unit or to the transformer itself.

It will therefore be seen that the use of my accessory will permit the transformers located in isolated spots and especially those transformers which are not subject to a regular inspection, to be operated at maximum efficiency without danger of being destroyed.

In describing my device in detail reference may be had to the accompanying drawing wherein a selected embodiment of the invention is illustrated, and in this drawing

Fig. 1 is a sectional view of the device showing the several parts in normal operating relation;

Fig. 2 is a sectional view of part of my device showing a modified construction for holding two contacts together for normal operation; and

Fig. 3 is a perspective view of a plug adapted to be employed in the construction shown in Fig. 2.

Referring now to this drawing, the accessory or unit preferably consists of an insulating casing 1 provided with a stationary contact 2 and a suitable movable contact 3, a current conducting plug 4, affixed in one end of the casing, a spring 5 to move contact 3, and a flexible current conducting cable 6 connecting the contact 3 and the plug 4. The contacts 2 and 3 are held in normal current conducting relation by a suitable alloy 7 which is preferably in solder form or is soldered in position. This particular construction of my device illustrates one manner in which the alloy is employed so that it may be melted to permit the contacts to separate thereby opening the energy circuit.

I have found that the construction illustrated in Fig. 1 is a very high efficiency from both the manufacturing and the operating standpoints. The casing 1 is preferably cylindrical and is easily fabricated from the ordinary fibre or other insulating tubing. The contact 2 and the plug 4 are readily assembled in the opposite ends of the casing and may be held in position by suitable means such as suitable screws. For purposes of obtaining a large contacting surface between the contacts 2 and 3, I have bored out contact 2 so that it will receive the contact 3 in a telescoping manner. Preferably contact 3 is formed of metal tubing so that the circulating medium may have substantially equal effect on all of the alloy. The casing 1 and the contact 3 are provided with openings 9 and 10 respectively to permit the free circulation of the oil and it is to be understood that these openings may be formed at different points so as to obtain desired results for different conditions of operation.

The spring and flexible conductor means for joining the contact 3 and the plug 4 to produce the means for separating the contacts and for maintaining a current connection to contact 3, have been very successful in operation, but when desired other constructions may be employed to perform these functions. For purposes of properly positioning and guiding contact 3 when it is withdrawn from contact 2, I have provided suitable rings 11 which engage the interior of the casing and which are held in position by suitable screws 8.

The construction of my device permits it to be readily installed in each of the transformer lead-in conductors and to be positioned below the surface of the main body of the circulating oil. It is to be understood however, that the devices may be located elsewhere and have the oil squirted over them in such a manner that the alloy will be properly affected and preferably so that the quantity of oil will be sufficient to assist in extinguishing the arcs formed as the contacts separate.

As is well known in the operation of trans-

formers, the oil surrounds the core and the windings thereof and absorbs the heat created and then rises in temperature. The volume of the oil is large and therefore some 5 of it has an opportunity to cool while other portions are absorbing heat from the transformer parts, but in time the whole body of the oil becomes heated and is then not able to conduct the heat away from the core and 10 windings. At this point it is dangerous to further operate the transformer and my device then functions to open the circuit. The alloy employed in my device may be any combination of materials desired so long as 15 it is responsive to the thermal condition of the oil. It is usually arranged so that it is responsive at a temperature slightly below the maximum temperature at which it is safe to operate the transformer. 20 In Fig. 2 I have shown another manner of using the alloy. A cylindrical plug 12 shown in detail in Fig. 3 is formed of the alloy and is adapted to slip into opening 9 in the casing so that a lug 13 will engage ring 25 11 and thus hold contacts 2 and 3 in current conducting relation. The oil is permitted to pass through the plug 12 and thus has a direct heating effect thereon. The frictional engagement of contacts 2 and 3 may be arranged so that all of the force required to 30 keep contact 3 in engagement with contact 2 against the force of spring 5 will not be offered by the plug. Such an allocation of the resisting forces is of value in the devices constructed to transmit large amounts 35 of power.

In Fig. 2 I have illustrated one way of maintaining the plug in the device but other means may be employed. My preferred 40 method is to provide the plug with a head 14 which engages a groove 15 formed in the casing, thus I have provided against the slipping of the plug from the casing. An ear 45 16 adapted to engage notch 17 prevents the plug from turning so that lug 13 will always be in contact with ring 11 until it is melted permitting the contact 3 to be drawn away from contact 2.

It will be seen from the foregoing description 50 that I have provided a novel and simple means for protecting large and expensive apparatus, and I have so arranged my device that it is responsive to the condition of operation of the device but is not responsive 55 to temporary overloads in the energy circuit. I, however, wish to be understood that my device is particularly responsive to the operating conditions of the elements of the apparatus and not to the amount of energy 60 which passes through them. Ordinarily cut outs or fuses of this nature in electrical apparatus are responsive to the amount of power passing through the power lines and they give way to open the circuit by reason

of the existence of an abnormal amount of 65 power. In constructing my device so that it is responsive to the conditions of the operating elements of the apparatus, I provide the alloy in such amounts that the existence of abnormal amounts of power passing 70 through the alloy has no effect in so far as releasing the device to open the circuit is concerned by heating the alloy or otherwise. My device is perfected to open the current lines when the apparatus continues to operate under conditions which are detrimental 75 to the elements of the apparatus. It will be understood that while I have shown my device as being connected in series in the line of a transformer, I may connect my device 80 in a circuit which will control a circuit-breaker or any other desired form of means for releasing the transformer or other apparatus from its operation in the circuit.

Various changes and modifications may be 85 made in the construction illustrated, but such variations are considered as being within the scope of my invention as outlined in the subjoined claims.

I claim:

1. In a protective device constructed to operate when predetermined operating conditions have been reached, the combination of a casing perforated to allow a fluid to pass in engagement with the inside and outside thereof, a pair of elements supported by said casing so as to be normally held in operative relation to one another and adapted to be moved apart under predetermined operating conditions, said elements being 90 mounted to have said fluid pass in contact therewith, means for holding said elements in normal operative relation, said means being responsive to a predetermined condition of said fluid, and means for positively moving said elements out of normal operative relation when the predetermined operating conditions have been reached. 95

2. In a protective device constructed to operate when predetermined operating conditions have been reached, the combination of a casing perforated to allow a fluid to pass therethrough, a pair of elements supported within said casing and being so mounted as to be normally held in operative relation to one another and adapted to be moved apart under predetermined operating conditions, the perforations in said casing permitting the fluid to pass in contact with 100 said elements, means for holding said elements in normal operative relation and being responsive to the temperature condition of said fluid, said holding means being subjected to strains during said holding operation, and a resilient means affixed to one of 105 said elements for moving said element out of operative relation with the other element after said holding means has been acted 110 115 120 125

- upon by said fluid to cause said holding means to release said elements, said resilient means being mounted within said casing.
3. In a protective device constructed to operate when predetermined operating conditions have been reached, the combination of a casing perforated to allow the fluid to pass therethrough, a pair of electrical contacts mounted within said casing, an electrically conducting material associated with said contacts for holding the same in operative relation to one another to thereby permit electricity to be conducted through said device, and means associated with one of said contacts for continuously tending to move said contact out of its operative relation with the other contact, said contacts being supported in said casing so that a heat absorbing medium may engage said contacts when said device is positioned to have said heat absorbing medium brought into relation therewith.
4. An electrical device for protecting a large electrical apparatus, said device consisting of a casing, a stationary electrical contact therein forming one terminal of an electrical circuit which controls the operation of the apparatus, a movable contact for engagement with said stationary contact, said movable contact forming the other terminal of the control circuit, means associated with said movable contact and acting to move said contact from said stationary contact when said contacts are released, and a fusible material for holding said contacts together, said material adapted to conduct the current in said circuit from one terminal to the other without becoming heated by the passage of current therethrough, said device being placed in juxtaposition to said apparatus to have said fusible material responsive to the heat developed by said apparatus and by the separation of said contacts to release said apparatus from operation due to the existence of abnormal temperature of said apparatus.
5. A temperature limiting device for use with transformers consisting of a perforated casing, a stationary and a movable contact therein, a spring means tending to maintain the movable contact away from the stationary contact, and an alloy forming a part of said device and adapted to hold said contacts in current conducting relation, said casing arranged to admit the oil from the transformer into contact with said alloy to melt the same and interrupt the flow of current when the oil has reached a predetermined temperature.
6. A protecting device for use with electrical apparatus consisting of a perforated casing, a pair of contacts carried by said casing and being so arranged as to be automatically separated at a predetermined tempera-
- ture, and a low melting point alloy positioned within said casing in a manner to hold said contacts in normal operating relation, said casing adapted to be held in a circulating medium which acts upon said alloy to melt it and allow said contacts to separate, said medium acting to extinguish an arc formed by the separating of said contacts.
7. A protective device for use in transformers consisting of a perforated insulating tubing, electrical conducting pieces affixed within said tubing at the ends thereof, a metal tubing adapted to telescopically engage one of said pieces, a flexible electrical conductor engaging the other of said pieces and said tubing, a spring also engaging said last named piece and said metal tubing and tending to draw said metal tubing from said first named piece, and a fusible alloy adapted to hold said first named piece and said metal tube together to permit the passage of current, said device adapted to be immersed in the oil of the transformer so that the oil may fuse the alloy and allow the contacts to draw apart, said oil further acting to quench the arc formed by the separation of the conducting parts.
8. A device for opening the electrical current of a transformer under predetermined condition of operation of said transformer consisting of a perforated insulating tubing, a stationary contact affixed within one end of said tubing, a perforated movable contact adapted to telescope into said stationary contact, a current conducting plug affixed in the other end of said tubing, a spring engaging said movable contact and said plug tending to withdraw said movable contact from said stationary contact, a flexible current conductor joining said movable contact and said plug and being located within said spring, and a fusible alloy for holding the telescoping contacts in current conducting relation, said device adapted to be immersed in the oil of the transformer so that the oil passes through the perforations and into contact with the fusible alloy and said contacts, said alloy arranged to be melted by the oil at a predetermined temperature thereby allowing said contacts to separate and said device being so constructed that the oil acts to extinguish an arc formed by the separating of said contacts.
9. In a device of the character described the combination of relatively movable elements adapted to be held in normal operating position, and a thermal responsive member for maintaining said elements in operative relation, said device adapted to be immersed in a medium of greater density than air which acts upon said thermal responsive member and which operates to prevent injury to said device when said relatively

movable elements are moved out of normal operating position.

10. In a device of the character described, the combination of relatively movable contacts normally held in current conducting relation against the opposition of a resilient member, a thermal responsive alloy interposed between said contacts for holding them in normal position, the amount of said 10 alloy being sufficient to conduct excessive currents due to abnormal disturbances with-

out becoming sufficiently heated to release said contacts, said device being subjected to a heat absorbing medium which operates to melt said alloy to permit the separation of said contacts and operates to extinguish dangerous arcs formed by the separating of said contacts. 15

In testimony whereof, I have signed my name to this specification this 19th day of October 1922.

W. WARREN WOODRUFF.
